DOUBLE-WALLED INSULATED TANK CAR
CONSTRUCTION

James G. Van Vleet, Kenmore, N. Y., assignor to
The Linde Air Products Company, New York,
N. Y., a corporation of Ohio

Application August 19, 1939, Serial No. 290,973

3 Claims. (Cl. 105—358)

This invention relates to a double-walled insulated tank car construction which is adapted for storing and/or transporting a liquefied gas, such as liquid oxygen, and more particularly to a construction for liquid baffles in the inner cylindrical vessel of such tank cars, the space between the vessels being preferably filled with a suitable insulating powder and evacuated.

The invention has for its object generally the provision of an improved construction for liquid baffles in the inner vessel of double-walled insulated tank cars in a manner which incorporates strength and imparts stiffness to the wall of the inner vessel, as well as reducing surging and splashing of the liquid which is being transported.

Another object is to provide a liquid baffle construction for the liquid containers of vacuum insulated tank cars, which is secured in the liquid container in a manner which braces the cylindrical walls of such containing vessels, and prevents excessive pressure on the end walls during surges.

Still another object is to provide a shape and disposition for liquid baffles in tank cars of the character indicated which is adapted to control the surging and splashing of liquid within the containing vessel together with an arrangement for insuring both liquid and gaseous equilibrium at all times when the tank car is in service.

Other objects of the invention will in part be obvious and will in part appear hereinafter.

The invention accordingly comprises the features of construction, combination of elements and arrangement of parts, which will be exemplified in the construction hereinafter set forth and the scope of the invention will be indicated in the claims.

For a fuller understanding of the nature and objects of the invention, reference should be had to the following detailed description taken in connection with the accompanying drawings, in which:

Fig. 1 is a view of a construction for double-walled insulated tank cars, partly in elevation and partly in vertical section (the plane of the section passing through the longitudinal axis of the car), which is adapted for storing and/or transporting liquid oxygen in accordance with the invention;

Fig. 2 is a fragmentary sectional view showing the construction and position of the baffle means shown in Fig. 1; and

Fig. 3 is a sectional view of the inner vessel taken on the line 3—3 of Fig. 1, showing in end

elevation the construction of the anti-splash baffles employed in the inner vessel.

Referring now to the drawings, and particularly to Figs. 1 and 2, 10 denotes an external frame, two or more of which may be provided for supporting the cylindrical wall of an inner vessel 11. The vessel 11 also has end walls and is adapted to hold the liquefied gas that is to be placed or stored in the tank car either with or without the aid of a lining or basket (not shown). 10 Outside of the vessel 11 and spaced therefrom is a second or outer vessel 12 which is also supported from the frames provided, the manner of support being hereinafter more fully explained. The space between the vessels is a closed space 15 and has no communication with the outside except that provided through certain evacuating connections, hereinafter described. The cylindrical wall of the outer vessel 12 is preferably braced against collapse and to this end is shown 20 provided interiorly with one or more stiffening rings 12'.

A gas withdrawal or evaporation connection 13 is provided leading from a point at one side of the car frame outside the outer vessel to a point 25 within the inner vessel; a similar connection 13' being provided for the other side, the inner ends of these connections being preferably protected by suitable anti-splash baskets, as shown respectively at 130 and 130'. A liquid supply and 30 withdrawal connection 14 is also provided leading from a point near the bottom of the vessel 11 to a suitable external point at one side; a similar connection 14' being preferably provided and arranged to lead from the same point for 35 the other side. The common outlet opening is provided with a protected liquid controlling means, shown generally at 15. This controlling means when open permits communication with a header 19 to which the connections 14 and 14' 40 are attached. The outer ends of these connections when not in use may be protected if desired by removable plates. When the end of a connection is open, or the plate removed, such connection may be coupled to a filling or discharge conduit, as the case may be, at a filling or 45 consuming plant.

Each of the connections 13, 13', 14, and 14' is preferably provided, at the point where it passes through the wall of the vessel 12, with a poor 50 heat conducting seal, for example, a relatively long conical wall, as shown at 16, which may be welded or otherwise integrally attached to the wall of outer vessel 12, as well as to the connection. The vessel 11 may be provided with auxil- 55

- iary connections, for example, as shown at 14a and 14b, for one or more trycocks. Other standard accessories, such as a liquid level gauge, may also be connected with the vessels.
- 5 The inner vessel 11 is here shown as provided additionally with an emergency liquid withdrawal connection 17 which has a portion 18 depending into the vessel and reaching substantially to the bottom. From an elbow at the top, 10 the connection leads down, to communicate with a horizontal passage in the header 19 which is here shown as a multi-way device that has a vertical passage communicating with the controlling means 15 and additional horizontal side 15 passages leading to the pair of oppositely extending connections 14 and 14'.
- In tank cars of the character here provided, the inner and outer vessels are, of course, cylindrically shaped vessels and the frames 10 which support 20 the same are each constructed to be relatively narrow structures each made of one or more plate members with an open and cut-away central portion shaped to permit the snug passage of the outer vessel 12 through the same and its rigid 25 attachment thereto, as by welding or the like. Each frame 10 is mounted on the car frame and disposed at right angles to the longitudinal axis of the car. The car frame may, of course, be of any suitable form, but is here shown as consisting 30 of a center sill 20 that may include side sills (not shown). The car frame, as shown, is provided with the usual bolsters depicted at 21, to which are pivotally connected the car trucks. To provide firm support for the frames 10 on the car 35 frame, a corresponding number of auxiliary bolsters 22 are incorporated in the frame. These may be adjacent to but displaced from the main bolsters. A strengthening plate 23 is preferably interposed, as shown at the end of the car frame, 40 between a bolster 22 and a frame 10, as indicated. The strengthening plate 23 thus provided is made fast, by riveting or otherwise, to the sills and bolsters of the car frame.
- In order to support the vessel 11 directly from 45 a frame 10 and not from the surface of the walls of vessel 12, a girth member or sling 24 is passed about the under side of vessel 11 adjacent an end of the same, the upper ends of each sling being provided with brackets or lugs as shown at 25.
- 50 Attached to each bracket is a sustaining rod or cable 26 of relatively low thermal conductivity which extends upwardly and outwardly and is secured at the upper end to the frame 10 in a suitable manner.
- 55 In order that the outer vessel 12 may be braced against end thrusts and otherwise afford additional support therefor, one or more web members, such as shown at 30, are interposed between the car frame and the outside wall of the vessel 60 12 at suitable points, for example, adjacent the auxiliary bolster 22. Such web members are conveniently formed by taking an I-beam and cutting off the bottom flange and then bending over the web so as to provide an angle-portion that may 65 be bolted to the plate 23 as indicated at 31, the top flange 32 of the I-beam being welded or otherwise arranged to make imperforate engagement with the outer wall of the vessel 12.
- In order that the inner vessel 11 may also be 70 braced against end thrusts and at the same time accommodate expansion and contraction of the same, the inner vessel 11 is supported at each end from the adjacent end of vessel 12 by tension suspension means. Such means is here shown as 75 comprising a plurality of horizontally disposed brackets or lugs 35 disposed circumferentially about and secured by welding adjacent each end of vessel 11. Attached to each of the brackets is a tension rod or cable 36 which is anchored in a receptacle 39 in the end wall of vessel 12. Such rod or cable extends generally horizontally but flares outwardly toward the edge of the adjacent end of vessel 12, the outer end of the anchoring receptacle being closed in a gas-tight manner, for example, by means of a closure cap 39.
- In order that the vessel 11 may also be braced against side swaying, a third set of supporting and staying means is applied to the inner vessel. This third means, as shown in Fig. 1, comprises one or more brackets 45 made fast by brazing or 15 welding to the end wall of vessel 11. From each of the brackets 45 extends downwardly and outwardly a rod or cable 46 which is of a material of relatively low thermal conductivity and has its end anchored in a receptacle 48 in the end wall of 20 vessel 12 and hermetically sealed.
- The anchorage for the staying means, above described, may tend to an undesirable concentration of stress at certain points unless suitable stress redistributing means are employed. In the 25 present invention, such means resolve the stresses and redistribute the same. This is here accomplished in connection with the receptacles 39 by means of a truss-like structure on the end wall of vessel 12. As shown, this structure comprises a 30 central ring 50 mounted on the end of vessel 12 and preferably concentric therewith, from which extend a plurality of radial members 51 distributed thereabout at points adapted to embrace the sides of each housing 39, the whole being made fast 35 thereto by welding or brazing. A thrust member, as shown at 52, is also advantageously incorporated in this structure and completes a rigid 40 triangular frame with the radial members that transmits the stress. By such means the end bracing takes up and converts the compression stress transmitted to a cylindrical portion of the outer wall of vessel 12. The supporting means above described is no part of the present invention, the same being disclosed in copending applications 45 filed respectively in the name of O. A. Hansen on August 19, 1939, Serial No. 290,970, and in the name of G. H. Zenner, et al. on August 19, 1939, Serial No. 290,971. Such suspending means, however, introduces stresses at certain points in the 50 wall of the inner vessel.
- In accordance with the present invention, liquid baffling means are employed, preferably in the form of one or more baffle plates 60 that are dished, as shown in Figs. 1 and 2, and disposed at 55 desired intervals along the axis of the inner vessel, in order to reduce or eliminate splashing and surging of the liquid when the tank car is being transported. Such baffle plates each have a diameter 60 adapted to fit snugly against the inner wall of the vessel 11 to which they are securely attached, as shown in Fig. 3. Each of these baffle plates is also provided with one or more openings 61 at the bottom which pass liquid, and with one or more openings at the top, such as shown at 62, for passing gas, in order that there may be equilibrium 65 in the gas phase and in the liquid at all times in the several compartments into which the baffle plates divide the vessel 11.
- The liquid filling and withdrawal controlling means shown is no part of the present invention. That shown, however, is seen to have an internally actuated valve in order to avoid loss of liquid 70 from the vessel 11 in the event of any injury to a 75

withdrawal connection, such as shown at 14 and 14'. The internal valve is actuated by a valve rod 153 passed downwardly through the walls of vessel 12 and vessel 11, respectively, a handwheel 154 being provided at the top of the rod in order to afford manipulation of the valve member from a convenient point outside the vessel 12. Means are provided for effecting passage of the valve rod 153 in a gas-tight manner without in any way interfering with the hermetic seal of the space between the walls of vessels 11 and 12. To this end, an external packing gland 155 is shown about the valve rod at the top of vessel 12, which packing gland is disposed in a dome 156 that has a flange 15 sealed in a suitable ring or collar 157, the latter being welded in the opening provided in the top of vessel 12. An expansible bellows 158 extends from the base of the packing gland 155 to the top of a second dome 159 sealed in the wall of the inner vessel in substantially the same manner as the dome 156.

The outer vessel 12 has one or more openings serving as manholes and through which access is had for the purpose of disposing a filling of a substantially dry heat insulating material in comminuted form in the space between the walls of the inner and outer vessels. One such manhole is shown at 160 in the top wall of the outer vessel. Another is shown at 161 near the bottom of the end wall of vessel 12. Such manhole covers are soft soldered or brazed in place in order that the space between the inner and outer vessels may at all times be hermetically sealed.

The hermetically sealed space between vessels 11 and 12 here provided is evacuated when the tank car is in service, this evacuation being conveniently accomplished by providing a connection in the wall of the outer vessel through which a vacuum pulling means may be connected to the space between the walls. Any suitable vacuum pulling means for this purpose may be employed, for example, a mechanical vacuum pump, which is preferably applied until a vacuum of the order of 0.1 mm. of mercury is pulled. The insulating material which fills the intervening space and the order of the vacuum pulled are no part of the present invention, the same being disclosed in copending application filed December 7, 1939, in the name of L. I. Dana, Serial No. 307,945.

In operation, the tank car of the present invention is filled with liquefied gas at a production plant by connecting a connection at 14 to a suitable source, such as a storage tank containing liquid oxygen, and a filling of liquid forced into the vessel 11 by means of pressure provided in any known manner. As the vessel 11 is filled, gas is displaced from the vessel through the connections 13 or 13'. When liquid can be withdrawn through the proper trycock connection, such as that at 14a, it is known that the vessel 11 is properly filled, and the filled tank car is then moved from the source of supply to a consumer installation for the delivery of a charge of liquid oxygen thereto.

In transit, it is seen that the inner and outer vessels are braced against end thrusts and side swaying. Also, it is seen that the baffle plates 60 operate to divide the liquid charge into a plurality of small bodies that are in fluid communication at the bottom so that when in equilibrium all will be at the same liquid level in vessel 11. These plates, by reason of their being dished have relatively great strength and operate to break up any longitudinal rush of liquid in the

vessel and hence reduce surging and splashing of the liquid which might otherwise result in substantial loss of liquid. The plates 60 are at the same time seen to stiffen the wall of vessel 11.

When it is desired to withdraw liquid from the vessel 11, the handwheel 154 is normally manipulated and the valve at 15 opened and liquid permitted to pass out under the influence of gravity through either connection 14 or 14'. In the event that the valve should fail to open, then pressure is generated in the vessel 11 by closing the gas connections 13 and 13'. When sufficient pressure has been built up the gas forces liquid up the connection 18 until it passes the elbow, where liquid will flow freely through the connection 18 into the header 19 and thence delivered through either connection 14 or 14'. Relatively large quantities of liquid oxygen may thus be safely shipped to and delivered at the consumer installation.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In double-walled insulated tank cars, the combination with an inner cylindrical vessel having end walls and adapted for holding a liquefied gas, of an outer cylindrical vessel having end walls surrounding and spaced from said inner vessel in a manner such that a closed space intervenes, a car frame for carrying said vessels, supporting frames disposed on said car frame at desired points and separately connected with each of said vessels, tension suspension means in said space connecting each end of said inner vessel to the adjacent end wall of said outer vessel whereby stresses are produced in the cylindrical wall of said inner vessel at the point of connection thereto, a plurality of transversely vertical baffle plates disposed snugly in and securely attached to the inner wall of said inner vessel in a manner reacting against said stresses and imparting strength thereby permitting a reduction in the ordinary thickness of the cylindrical wall of said inner vessel, and communicating means in said baffle plates comprising upper and lower passages therein.

2. In double-walled insulated tank cars, the combination with an inner cylindrical vessel having end walls and adapted for holding a liquefied gas, of an outer cylindrical vessel having end walls surrounding and spaced from said inner vessel in a manner such that a closed space intervenes, a car frame for carrying said vessels, supporting frames disposed on said car frame at desired points and separately connected with each of said vessels, tension suspension means in said space connecting each end of said inner vessel to the adjacent end wall of said outer vessel whereby stresses are produced in the cylindrical wall of said inner vessel at the point of connection thereto, a plurality of substantially transversely vertical dish-shaped baffle plates having flanges fitted against and securely attached to the inner wall of said inner vessel, at least certain of said baffle plates being substantially at the points of said localized stresses and imparting resistance to stress to the wall of said inner vessel.

and communicating means for said baffle plates comprising upper and lower passages therein.

3. In double-walled insulated tank cars, the combination with an inner cylindrical vessel having end walls and adapted for holding a liquefied gas, of an outer cylindrical vessel having end walls surrounding and spaced from said inner vessel in a manner such that a closed space intervenes, a car frame for carrying said vessels, supporting frames disposed on said car frame at desired points and separately connected with each of said vessels, tension suspension means in said space connecting each end of said inner vessel to the adjacent end wall of said outer vessel whereby stresses are produced in the cylindrical

wall of said inner vessel at the point of connection thereto, a plurality of substantially transversely vertical dished baffle plates in equal numbers and symmetrically disposed in each end of said inner vessel, each of said baffle plates having flanges fitting snugly against and securely attached to the inner wall of said inner vessel, at least certain of said baffle plates being substantially at the points of said localized stresses and imparting resistance to stress to the wall of said inner vessel, and communicating means for said baffle plates comprising upper and lower openings therein.

JAMES G. VAN VLEET. 15
